DIALKYL ESTERS OF N-SUBSTITUTED
ASPARTIC ACID AND METHOD OF PRE-
PARING THE SAMEKathryn L. Lynch, Riverside, Conn., assignor to
American Cyanamid Company, New York,
N. Y., a corporation of MaineNo Drawing. Application September 25, 1940,
Serial No. 358,314

10 Claims. (Cl. 260—471)

This invention relates to new and useful dialkyl esters of N-substituted aspartic acid and methods of preparing the same.

I have found that higher alkyl esters of N-substituted aspartic acid can be prepared simply by reacting with a primary amine a dialkyl ester of maleic acid in which the alkyl group contains 4 or more carbon atoms. The resulting compounds are surface-active agents of the cation-active type and have been found to possess remarkable wetting and detergent properties. They are well suited for wetting wool, cotton, cellulose acetate, cellulose nitrate, viscose and similar threads and fibres; for demulsification of petroleum emulsions; in the impregnation of cellulosic fabrics with latex dispersions; dye assistants; in pickling baths; and other uses which will appear evident to those skilled in the art. A particularly valuable feature of my new compounds is that while they possess marked wetting properties, solutions thereof have at concentrations in which wetting agents are normally employed non-foaming characteristics, which is contrary to the normal behavior of wetting agents.

I have found that the dialkyl maleates obtained by esterifying maleic acid with alcohols of 4 or more carbon atoms can be condensed with primary alkylamines or primary hydroxy arylamines and

hydrocarbon radicals and R is a member of the group consisting of alkyl and aryl hydrocarbon radicals, the following reaction is found to take place:

Thus, for example, monoethanolamine will react with the diamyl ester of maleic acid to form diamyl N-(2-hydroxyethyl) aspartate according to the following reaction:

In addition to the above condensation there are several side reactions that occur simultaneously but at a much slower rate, the most important being as follows:

their esters and ethers to form new derivatives of N-substituted aspartic acid. When a dialkyl maleate of the formula:

in which R₁ and R₂ are members of the group consisting of hydrogen and alkyl and aryl hydrocarbon radicals, and R₃ and R₄ are alkyl radicals of more than 4 carbon atoms, is mixed with a primary amine having the formula XO—R—NH₂, in which X is a member of the group consisting of hydrogen, acyl radicals, and alkyl and aryl

40 45 A similar reaction involves the conversion of the dialkyl ester of the N-substituted aspartic acid to the corresponding diamide. In addition there appears to be a conversion of maleate ester to fumarate ester occurring to a small extent. In general, it appears that the rate of addition of monoethanolamine to dialkyl fumarate is very slow.

In order to obtain good yields of the aspartic ester, it is evident that the reaction should be interrupted by removal of unreacted amine when the principal condensation reaction has slowed to a rate comparable with the rate of one or more of the above side reactions. The esters of low molecular weight react more rapidly than the higher members of the series and within a shorter time,

and therefore the point of interruption will be determined in each case by the skilled chemist. For example, the addition of the primary amines to the double bond of the maleate ester is substantially complete within 20-30 minutes for the diamyl ester, at which time approximately 65% of the amine has been converted to aspartate, 20% being still unreacted and 15% having been used up in the side reactions mentioned above. I have found that by washing a hydrocarbon solution of the dialkyl N-substituted aspartate with water, the unreacted primary amine is removed and the further conversion of the ester to amide is prevented. By this procedure it is possible to obtain yields of from 50% to 75% of the theoretical.

I have found that it is preferable to use primary amines in the above way in the preparation of my new compounds as secondary and tertiary amines do not readily condense at the double bond of maleic esters. The reaction products of maleic esters with secondary amines consist mostly of amides, imides and aminic esters, as the reaction at the double bond is very slow. The primary amines which I have found useful in the practice of my invention are those having the general formula $XO-R-NH_2$ where X is a member of the group consisting of hydrogen, acyl radicals, and alkyl and aryl hydrocarbon radicals and R is a member of the group consisting of alkyl and aryl hydrocarbon radicals. For example, I have found that I may use monoethanolamine, mono-isopropanolamine, para-aminophenol, or esters or ethers thereof such as amyl oxypropylamine, amyl oxyethylamine, or the acetyl, propionyl or butyryl or benzoyl esters of the corresponding alkylolamines.

Dialkyl esters of maleic acid capable of condensing with the above and similar amines to form wetting agents in accordance with my invention have the general formula

in which R_1 and R_2 are members of the group consisting of hydrogen and alkyl and aryl radicals and R_3 and R_4 are alkyl radicals of 4 or more carbon atoms. R_1 and R_2 are non-functional groups; i. e. they take no part in the condensation of the primary amine with the dialkyl ester, but they influence the wetting properties of the finished product. R_3 and R_4 may represent the same or different alkyl radicals of 4 or more carbon atoms, as for example R_3 may be a hexyl and R_4 may be an octyl radical. Specifically R_3 and R_4 may be n-butyl, amyl, hexyl, octyl, methyl amyl, ethyl hexyl, capryl, decyl, lauryl, stearyl and the like radicals. Specific examples of the dialkyl esters that may be employed in my invention are diamyl maleate, dibutyl maleate, dicapryl maleate, di-(methyl amyl) maleate, di-(ethyl hexyl) maleate, di-n-hexyl maleate, didecyl maleate, dihexyl- α -phenyl maleate, dihexyl citraconate, dicapryl pyrocinchonate, hexyl octyl maleate and the like.

In preparing the new compounds of my invention, equimolecular proportions of the dialkyl maleate and primary amine are preferably mixed at room temperatures and the reaction is allowed to proceed for 10 minutes to 3 hours or until the principal reaction approaches the rate of the side reactions, as explained above. The reaction products may then be dissolved in mineral spirits such as kerosene, toluene, and sim-

ilar hydrocarbon solvents or, if desired, the reaction may be carried out in the presence of the hydrocarbon solvent. Unreacted primary amine is preferably removed by repeated washings with water.

The dialkyl N-substituted aspartate formed in the reaction may be recovered from the hydrocarbon solution by bubbling dry HCl through the water-free solution at 10-25° C. until saturated, whereby it is precipitated as the hydrochloride. If desired the precipitate may be recrystallized from dioxane. Another method of recovering the dialkyl N-substituted aspartates consists in extracting the hydrocarbon solution with the theoretical amount of HCl in water to remove the water-soluble hydrochloride. Evaporation of the clear aqueous solution yields the crude hydrochloride, which may be purified by redissolving in water, adding excess Na_2CO_3 and extracting the water-insoluble free base with ethyl ether. The hydrochloride may be precipitated from the ethyl ether by treatment with dry HCl as described above.

For reasons well-known to those skilled in the art amine bases of the type represented by my compounds are generally isolated and handled in the form of the hydrochloride or other acid salts. Consequently, when I speak of my dialkyl N-substituted aspartate I mean to include these compounds in their combined form. It has been found that although it is possible to prepare my compounds in the form of the free base, the hydrochloride is more stable and better suited for handling and storage purposes.

The invention will now be illustrated in greater detail by means of the following specific examples. It should be understood, however, that although these examples may describe in detail some of the more specific features of the invention, they are given primarily by way of illustration and that the invention in its broader aspects is not to be limited thereto.

EXAMPLE 1

45 512 g. (2 moles) of diamyl maleate and 122 g. (2 moles) of mono-ethanolamine were mixed at 25° C. and the reaction started. Cooling in ice water was required to keep the temperature below 74° C. 1350 cc. of mineral spirits were added 50 and unreacted ethanolamine was removed by washing with three 500 cc. portions of water. The diamyl N(2-hydroxyethyl) aspartate formed in the reaction was precipitated as the hydrochloride by bubbling dry HCl through the hydrocarbon solution at 10-25° C. until saturated. The precipitated hydrochloride was removed by centrifuging and purified by recrystallization from dioxane. The product was the hydrochloride of diamyl N(2-hydroxyethyl) aspartate, a white crystalline powder readily soluble in water and melting at 108.5° C.

When monopropanolamine was substituted for monoethanolamine in equivalent quantities a product of similar characteristics was obtained. Attempted condensations with diethanolamine, however, were unsuccessful.

The wetting power of diamyl N(2-hydroxyethyl) aspartate prepared as in Example 1 was measured by the standard Draves sinking time test. This method consists of measuring the time required for a five gram skein of gray 2-ply cotton yarn to sink in a solution of the wetting agent when the skein, carrying a 1½ gram sinker, is held below the surface of the solution 70 by a heavier weight called the anchor. Different

concentrations of the wetting agent are made and the time is taken for the different concentrations to make the yarn sink. The results were as follows:

Draves sinking time test at 30° C.

Grams per liter--- 5.0 2.5 1.5 1.25 1.0 0.75
 Time in seconds--- <2 3.9 11.5 19.5 32.9 83.0

Dimethyl N-butyl aspartate prepared by a process generally similar to that used in Example 1 possessed no wetting or foaming properties in water.

EXAMPLE 2

Diamyl maleate and monoethanolamine were reacted as in Example 1. A benzene solution of the free base was washed with water to remove unreacted amine and the solution was then extracted with the theoretical amount of HCl in water to remove the water-soluble hydrochloride. Evaporation of the clear aqueous layer gave an 88% yield of the crude hydrochloride. This was purified by redissolving in water, adding excess Na_2CO_3 and extracting the water-insoluble free base with ethyl ether. The product was then precipitated as the hydrochloride by saturating the solution with gaseous HCl. Its properties were as described in Example 1.

The purification method of this example may be employed for the recovery of any of the N-substituted aspartic acid esters of the present invention. Thus, for example, dibutyl N(2-hydroxyethyl) aspartate, diamyl N(hydroxypropyl) aspartate, dihexyl N(p-hydroxyphenyl) aspartate, dicapryl N-(3-hydroxypropylamino) pyrocinochonate, dihexyl- α -(N-2-hydroxyethylamino) α -phenyl succinate, hexyl octyl N(2-hydroxyethyl) aspartate, and like compounds produced according to my invention may be dissolved in benzene, kerosene, toluene or similar hydrocarbon solvents and then washed with water to remove unreacted amine and other water-soluble secondary reaction products. The hydrocarbon solution may then be washed with HCl in water to remove the aspartate in the form of its water-soluble hydrochloride. The aqueous solution may be evaporated, redissolved in water, treated with Na₂CO₃ and extracted with ethyl ether and then precipitated from the ethyl ether solution with gaseous HCl as described above.

EXAMPLE 3

30.5 g. (0.5 mole) of monoethanolamine and 142 g. (0.5 mole) of di-methylamyl maleate were mixed at 24° C. During the course of the reaction the temperature rose to 64° C. After a reaction time of about one hour the unreacted amine was removed by washing a mineral spirit solution of the product as in Example 1. Saturating the mineral spirit solution with HCl caused the separation of a liquid layer from which di-methylamyl-N-(2-hydroxyethyl) aspartate hydrochloride was separated by extracting with water. The dry product was obtained in 65% yields by evaporation of the aqueous solution.

The wetting power of the product was determined by the Draves test with the following results:

Draves sinking time test at 30° C.

Grams per liter----- 3.0 2.0 1.5 1.0 0.5 70
 Time in seconds----- 7.6 12.7 18.4 29.2 73.0

EXAMPLE 4

170 g. (0.5 mole) of di-(2-ethylhexyl) maleate and 30.5 g. (0.5 mole) of monoethanolamine were

combined as in Example 3. Benzene was added and the unreacted amine extracted with water. The diethyl N-(2-hydroxyethyl) aspartate hydrochloride was separated as a syrupy semi-solid which displayed no tendency to crystallize.

A Draves test on the product gave the following result:

Draves sinking time test at 30° C.

10 Grams per liter----- 1.8 0.9 0.72
Time in seconds----- 34.0 55.5 66.0

EXAMPLE 5

15 To 568 g. (2 moles) of di-n-hexyl maleate and
534 g. mineral spirits, were added 125 g. (2
moles + 2.5% excess) of monoethanolamine with
agitation. The temperature rose to a maximum
of 52.5° C. After the reaction had proceeded for
30 minutes, 200 cc. of wash water were added.
20 This was followed by two 200 cc. washes with
water. 135 cc. concentrated HCl were added to
the opaque mineral spirit solution with cooling
and stirring. The di-n-hexyl N(2-hydroxy-
ethyl) aspartate hydrochloride which separated
25 from the solution was filtered and dried. The
product was obtained in the form of tiny white
plate-like crystals of a pearly lustre and wax-
like feel.

30 A sample of di-n-hexyl N(2-hydroxyethyl) aspartate hydrochloride gave the following results in the Draves test.

Draves sinking time test at 30° C.

Grams per liter 1.8 0.9 0.72
 Time in seconds 11.2 20.4 31.5 44.4 66.9

EXAMPLE 6

40 g. (0.1 mole) didecyl maleate and 69 (0.1 mole) monoethanolamine were mixed at 25° C. The temperature rose on stirring to 55° C. The reaction mixture was allowed to cool to 45–50° C. and an equal volume of mineral spirits was added. The solution was washed three times with water to remove excess monoethanolamine and half ester salts formed in the reaction. 8.3 cc. concentrated HCl (0.1 mole) were added to the mineral spirit solution with cooling. A white waxy solid of the hydrochloride of didecyl N(2-hydroxyethyl) aspartate precipitated almost at once.

50 The product is soluble in hot water to give opaque foaming solutions which do not precipitate on cooling.

What I claim is:

1. A process for the production of dialkyl esters
55 of N-substituted aspartic acid of the formula

in which R is a member of the group consisting of alkyl and aryl hydrocarbon radicals, and R₃ and R₄ are alkyl radicals of at least 4 carbon atoms said esters having wetting and detergent properties, which comprises reacting a primary amine having the formula HO—R—NH₂ in which R is as defined above, with a dialkyl ester of maleic acid of the formula

in which R_3 and R_4 are alkyl radicals of at least 4 carbon atoms.

CERTIFICATE OF CORRECTION.

Patent No. 2,324,712.

July 20, 1943.

KATHRYN L. LYNCH.

It is hereby certified that error appears in the printed specification of the above numbered patent requiring correction as follows: Page 3, second column, line 33, Example 5, for

" Grams per liter ----- 1.8 0.9 0.72"

read

--Grams per liter -- 1.0 0.5 0.3 0.2 0.125--;

and that the said Letters Patent should be read with this correction therein that the same may conform to the record of the case in the Patent Office.

Signed and sealed this 7th day of September, A. D. 1943.
